PRODUCTION OF ALPHA-NITROKETONES

Gustave B. Bachman, Lafayette, Ind., and Takeo Hokama, Pittsburgh, Pa., assignors to Purdue Research Foundation, West Lafayette, Ind., a corporation of Indiana

No Drawing. Filed May 8, 1959, Ser. No. 811,800
8 Claims. (Cl. 260—592)

Our invention relates to the production of alpha-nitroketones. More particularly, it relates to the production of alpha-nitroketones by the C-acylation of primary nitroalkanes with acyl cyanides under basic conditions.

Although alpha-nitroketones were first prepared in 1898, the chemical properties of these compounds have not been investigated to any great extent, largely because of the difficulty in preparing these compounds. Most of the various methods which have been suggested in the literature for the production of alpha-nitroketones do not represent even good laboratory methods because of the low yields, complexity of reaction sequences, difficulty of separation procedures and limitations to specific functional groupings.

We have now discovered a method for the production of alpha-nitroketones which not only gives greatly improved yields of the desired compounds, but at the same time is free from most of the objectional features of the prior processes suggested for the preparation of these compounds. Our new process consists essentially of accomplishing the C-acylation of primary nitroalkanes with acyl cyanides under basic conditions whereby 30-70% yields of alpha-nitroketones are obtained. Our improved results are accomplished by effecting the acylation of a primary nitroalkane in the salt form using an acyl cyanide, the reaction being carried out under basic conditions and preferably in a suitable solvent.

Our process is applicable generally to the C-acylation of primary nitroalkanes; examples of which include nitromethane, nitroethane, 1-nitropropane, 1-nitrobutane, 1-nitrooctane, and so forth.

We have found that the particular salt of the primary nitroalkane used affects to a considerable degree the yield of C-acylation product. The exact reason for these variations is not known, but it is believed that they probably result from the different solubilities of the different primary nitroalkane salts. The lithium salts of the primary nitroalkanes, for example, were found to give higher yields than the corresponding sodium salts. The lithium salts are also easier to prepare than the corresponding sodium salts. In general, the more soluble the salt, the more highly reactive it is under our acylation conditions. We can, therefore, carry out our acylation process with any stable soluble metal salt of a primary nitroalkane. The silver salts, for example, are unstable and hence of little utility. The mercury salts are relatively insoluble and hence not reactive. We have found the alkali metal salts of the primary nitroalkanes to be the most satisfactory in our process.

As the acylating agent we can use acyl cyanides including alkanoyl cyanides such as acetyl cyanide, propionyl cyanide, butyryl cyanide and aroyl cyanides such as benzoyl cyanide.

Our acylation process is preferably carried out in a suitable solvent medium which must be a solvent for the nitroalkane salt, the acyl cyanide, and should be inert to both of these materials as well as the resulting acylated reaction products. The nitroalkane salts have limited solubilities in most organic solvents. One of the better types of solvent for these salts are tertiary aliphatic alcohols such as tertiary butanol. In ethanol and 2-propanol, for example, the reaction of the solvent with the acyl cyanide predominates and esters are the principal products.

2

Other suitable solvents include tetrahydrofuran, pyridine, ether, etc. Solvents which do not contain active hydrogens are ordinarily satisfactory for our process.

5 The acylation process can be carried out at temperatures ranging from 0-75° C. Ordinarily, the reaction can be satisfactorily effected at room temperature.

Our invention will be illustrated by the following specific examples. It should be understood, however, that we are not limited either to the specific amounts or ratios of added ingredients shown therein nor the specific method of mixing the reactants. It is understood that the usual variations and procedures obvious to one skilled in the art are included within the scope of our invention.

Example I

15 Nitromethane, 12.2 g. (0.2 mole), was added during a period of 15 minutes to a solution of sodium ethoxide formed by reacting sodium metal, 4.6 g. (0.2 mole), with ethanol (300 ml.) in a 500 ml. 3-necked flask equipped 20 with a stirrer, dropping funnel and reflux condenser protected with a sodium hydroxide drying tube. Benzoyl cyanide, 26 g. (0.2 mole), was added during a period of 30 minutes to the cooled suspension and a mixture was stirred for four hours. The suspension was filtered and the precipitated was washed with dry ether (100 ml.). The solid was partially dissolved in water (200 ml.) and acidified with dilute hydrochloric acid (3 N, 200 ml.) at 0.5° C. The suspension was filtered and the solid was dried and recrystallized from an ether-petroleum ether, B.P. 25 65-67° C., mixture. Yield of nitroacetophenone, 3 g. (9% theory), M.P. 105-106° C.

Example II

Sodium t-butoxide was formed by reacting sodium metal, 2.3 g. (0.1 mole), with t-butanol (dried over calcium 35 hydride), 300 ml., at a reflux temperature for 12-14 hours. 1-nitropropane, 18 g. (0.2 mole), was added during a period of 20 minutes to the cooled suspension and the mixture was stirred for 30 minutes. Benzoyl cyanide, 13 g. (0.1 mole), was added to the suspension during a period 40 of 30 minutes and the reaction mixture was stirred at room temperature for 5 hours. After the major portion of the solvent was removed under a water aspirator, the residue was taken up in a mixture of benzene (100 ml.), and water (200 ml.) and acidified with 10% acetic acid 45 solution (100 ml.). The benzene layer was separated and the aqueous solution was extracted three times with benzene (50 ml. portions). The combined benzene solutions were washed with water and dried over magnesium sulfate. Distillation gave benzoic acid, 4.0 g. and alpha-nitrobutyrophenone, 5.0 g. (26% theory), B.P. 115-118° C. (1 mm.), n_D^{25} 1.5326.

Example III

55 Lithium t-butoxide was formed by dissolving lithium metal, 0.7 g. (0.1 mole), in dry t-butanol (300 ml.) by heating the alcohol solution to a gentle reflux for two hours. 1-nitropropane, 18 g. (0.2 mole), was added during a period of 15 minutes to the cooled solution and the resulting mixture was stirred for 15 minutes. Benzoyl cyanide, 13 g. (0.1 mole), was added during a period of 30 minutes to the suspension and the mixture was stirred for four hours at room temperature. After the major portion of the solvent was removed under water aspiration, the residue was taken up in a mixture of ether (200 ml.) and water (200 ml.) and acidified with 10% acetic acid solution (100 ml.) containing urea, 10 g. The aqueous layer was extracted five times with ether (50 ml. portions) and the combined ether solutions were washed with water and dried over magnesium sulfate. Distillation gave alpha-nitrobutyrophenone, 12 g. (62% theory), B.P. 114° C. (1 mm.), n_D^{25} 1.5334.

Analysis.—Calculated for $C_{10}H_{11}NO_3$: C, 62.16; H, 5.74; N, 7.25. Found: C, 62.17; H, 6.00; N, 7.49.

Example IV

Using the above procedure, benzoyl cyanide, 22 g. (0.1 mole), was reacted with lithium ethanenitronate, 16.4 g. (0.2 mole), in t-butanol, 400 ml., for five hours at room temperature. Alpha-nitropropiophenone, 15 g. (50% theory), B.P. 124° C. (1-2 mm.), n_{D}^{26} 1.5434 was isolated on distillation.

Analysis.—Calculated for $C_9H_9NO_3$: C, 60.33; H, 5.06; N, 7.82. Found: C, 60.28; H, 5.40; N, 8.12.

Example V

Benzoyl cyanide, 13 g. (0.1 mole), was reacted with lithium 1-butanenitronate, 21.4 g. (0.2 mole), in dry t-butanol, 400 ml., according to the procedure outlined in Example III with lithium 1-propanenitronate. After six hours at room temperature, the reaction mixture was concentrated, taken up in a mixture of ether, 100 ml., and water, 400 ml., and acidified with 10% acetic acid solution, 200 ml., containing urea, 10 g. The ether layer was separated, and the aqueous layer was extracted three times with ether (50 ml. portions). The ether solution was washed with water, and dried over magnesium sulfate. The dried ether solution was chilled in a Dry Ice bath and alpha-nitrovalerophenone, 2.5 g. was precipitated and filtered. This operation was repeated several times with the mother liquor, and an additional 8.5 g. of solid was isolated and recrystallized from petroleum ether (B.P. 35-60° C.). A total of 11 g. (53% theory), of alpha-nitrovalerophenone, M.P. 48° C. was obtained.

Analysis.—Calculated for $C_{11}H_{13}NO_3$: C, 63.75; H, 6.32, N, 6.76. Found: C, 63.56; H, 6.06; N, 6.75.

Example VI

Benzoyl cyanide, 10 g. (0.077 mole), was added during a period of 30 minutes to a suspension of lithium 1-propanenitronate, 9.5 g. (0.1 mole), in dry pyridine (200 ml.), and the reaction mixture was stirred for a total of 8 hours at room temperature. The major portion of the solvent was removed under water aspiration and the residue was taken up in a mixture of ether (100 ml.) and water (200 ml.). The reaction mixture was acidified with 10% acetic acid solution (100 ml.) containing urea, 10 g., and the ether layer was separated. The aqueous layer was extracted three times with ether (50 ml. portions). The combined ether extracts were washed with water and dried over magnesium sulfate. The ether solution was concentrated, and the residual oil was distilled through a short Vigreux column under nitrogen at reduced pressure. Alpha-nitrobutyrophenone, 8 g. (54% theory), B.P. 128° C. (1-2 mm.), n_{D}^{26} 1.5336, was obtained.

Example VII

Following the same procedure outlined in Example VI, benzoyl cyanide, 10 g. (0.077 mole), was reacted with lithium 1-propanenitronate, 9.5 g. (0.1 mole), in tetrahydrofuran (200 ml.) at room temperature for four hours and at 65° C. for one hour. Alpha-nitrobutyrophenone, 9 g. (60% theory) was isolated.

Example VIII

The procedure described in Example VI was used for the reaction of benzoyl cyanide, 10 g. (0.077 mole), with lithium 1-propanenitronate, 9.5 g. (0.1 mole), in ether (200 ml.) at room temperature for 12 hours and at 35° C. for four hours. Alpha-nitrobutyrophenone, 1.9 g. (10% theory) was isolated.

Example IX

Benzoyl cyanide, 13 g. (0.1 mole), was added during a period of 0.5 hour to a mixture of nitromethane, 12 g. (0.2 mole), and sodium carbonate, 21 g. (anhydrous powder, 0.2 mole) in pyridine, 300 ml. (dried over calcium hydride), and the reaction mixture was stirred for

3.5 hours. The suspension was filtered and the precipitate was washed with dry ether (100 ml.). The solid was partially dissolved in water (400 ml.) and acidified with dilute hydrochloric acid (3 N, 200 ml.) at 0-5° C. Nitroacetophenone, M.P. 105-106° C., 12 g. (73% theory) was isolated by filtration and recrystallization from ether-petroleum ether.

Analysis.—Calculated for $C_8H_7NO_3$: C, 58.18; H, 4.27; N, 8.48. Found: C, 58.20; H, 4.37; N, 8.52.

Example X

Nitroethane, 30 g. (0.4 mole), was added during the period of 30 minutes to a cooled suspension of lithium t-butoxide prepared by reacting lithium metal, 1.7 g. (0.25 mole), with t-butanol (400 ml.), and the resulting mixture was stirred for a period of 30 minutes. Freshly distilled acetyl cyanide, 17 g. (0.25 mole), was added during a period of two hours to the suspension, and the mixture was stirred for two hours. After a major portion of the solvent was removed under water aspiration, the residue was taken up in a mixture of water, 200 ml., and ether, 100 ml., and acidified with 10% acetic acid solution (200 ml.) containing urea (10 g.). The aqueous solution was extracted five times with ether (100 ml. portions), and the combined ether solutions were washed with water and dried. The ether solution was concentrated and the residue was flash distilled in vacuo under nitrogen. Yield, 30 g., B.P. 20-90° C. (1 mm.). The crude product was fractionated through a two foot spiral column and pure 3-nitro-2-butanone, 11.6 g. (30% theory), B.P. 58° C. (1 mm.), n_{D}^{26} 1.4362 was isolated.

Example XI

The procedure described in Example X above was applied to the reaction of acetyl cyanide, 14 g. (0.2 mole), with lithium 1-propanenitronate, 16.2 g. (0.2 mole), in t-butanol (400 ml.). 3-nitro-2-pentanone, 9.5 g. (36% theory), B.P. 52° C. (1 mm.), n_{D}^{26} 1.4334, was isolated.

Analysis.—Calculated for $C_6H_9NO_3$: C, 45.79; H, 6.92; N, 10.68. Found: C, 46.00; H, 7.15; N, 10.94.

Example XII

The procedure described in Example X above was applied to the reaction of acetyl cyanide, 14 g. (0.2 mole), with lithium 1-butanenitronate, 21.4 g. (0.2 mole), in t-butanol (400 ml.). Slightly impure 3-nitro-2-hexanone, 11 g. (38% theory) B.P. 60° C. (1 mm.), n_{D}^{26} 1.4372 was isolated.

Analysis.—Calculated for $C_8H_{11}NO_3$: C, 49.64; H, 7.64; N, 9.65. Found: C, 50.68; H, 8.59; N, 10.48.

Now having described our invention what we claim is:

1. A process for the production of alpha-nitroketones which comprises reacting at temperatures ranging from 0 to 75° C., an acyl cyanide selected from the group consisting of alkanoyl cyanides and aroyl cyanides and an alkali metal salt of a primary nitroalkane dissolved in a tertiary aliphatic alcohol solvent medium for the nitroalkane salt, said solvent medium being substantially inert to the acyl cyanide, acidifying the thus produced reaction mixture and recovering the alpha-nitroketone thereby produced.

2. The process of claim 1 wherein the alkali metal salt of the primary nitroalkane is selected from the group consisting of the sodium salt and the lithium salt of a primary nitroalkane.

3. The process of claim 1 wherein the primary nitroalkane is selected from the group consisting of nitromethane, nitroethane, 1-nitropropane, and 1-nitrobutane.

4. The process of claim 1 wherein the inert solvent is t-butanol.

5. A process for the production of alpha-nitroketones which comprises reacting at temperatures ranging from 0 to 75° C., an alkanoyl cyanide and an alkali metal salt of a primary nitroalkane dissolved in a tertiary aliphatic alcohol solvent medium for the said salt of the

primary nitroalkane, said solvent medium being substantially inert to the alkanoyl cyanide, acidifying the thus produced reaction mixture and recovering the alpha-nitroketone thereby produced.

6. The process of claim 5 wherein the alkanoyl cyanide is acetyl cyanide and the primary nitroalkane is selected from the group consisting of nitromethane, nitroethane, 1-nitropropane, and 1-nitrobutane.

7. A process for the production of alpha-nitroketones which comprises reacting at temperatures ranging from 10 0 to 75° C., an aroyl cyanide and an alkali metal salt of a primary nitroalkane dissolved in a tertiary aliphatic alcohol solvent medium for the said salt of the primary nitroalkane, said solvent medium being substantially inert to the aroyl cyanide, acidifying the thus produced 15 reaction mixture and recovering the alpha-nitroketone thereby produced.

8. The process of claim 7 wherein the aroyl cyanide is benzoyl cyanide and the primary nitroalkane is selected from the group consisting of nitromethane, nitroethane, 1-nitropropane, and 1-nitrobutane.
